UNITED STATES PATENT OFFICE.

LOUIS E. DIERKS, OF CHICAGO, ILLINOIS, ASSIGNOR TO SAUERMAN BROTHERS, A PARTNERSHIP FIRM COMPOSED OF HENRY B. SAUERMAN AND JOHN A. SAUERMAN, BOTH OF CHICAGO, ILLINOIS.

MATERIAL-MOVING APPARATUS.

1,263,749.

Specification of Letters Patent. Patented Apr. 23, 1918.

Application filed December 5, 1917. Serial No. 205,587.

To all whom it may concern:

Be it known that I, LOUIS E. DIERKS, a citizen of the United States, residing at Chicago, in the county of Cook and State of Illinois, have invented a new and useful Material-Moving Apparatus, of which the following is a specification.

My invention relates to improvement in material-moving apparatus more particularly, though not exclusively, to apparatus of a type comprising, generally stated, an inclined cable-way supporting a traveling carriage thereon, with a scraper-bucket connected with the carriage, and a hauling line through the medium of which the movements of the carriage and bucket are controlled, the scraper-bucket being adapted to be filled at its forward end and to discharge, at the point of dumping, through its valve-equipped rear end.

As structures of this type have been usually constructed the bucket is so supported that it remains, during the opening of the valve at the dumping end of the bucket, in the dumping operation, in the same position it assumes in the movement of the bucket to dumping position.

As a result, either the bucket must be normally tilted to such a degree that objectionable friction is placed upon the gate at the discharge end of the bucket, in order that the bucket may discharge when operating on different kinds of material, or if such undue tilting is eliminated to reduce the friction on the valve mechanism, the material, if of certain kinds, will not freely discharge from the bucket.

My primary object is to provide an apparatus of the general type above stated, which will reduce to the minimum friction against the gate tending to prevent its turning in the dumping operation, and which will insure the dumping from the bucket of the charge of material therein regardless of the character of the material; and other objects as will be manifest from the following description.

Referring to the accompanying drawings— Figure 1 is a view in side elevation of apparatus constructed in accordance with my invention for transferring material from a lower to a higher elevation, the apparatus being shown in the position it assumes im-

mediately before dumping or, in other words, during the load-carrying operation. 55

Fig. 2 is a similar view showing the parts in dumping position.

Fig. 3 is a similar view of a modification of the construction shown in Fig. 1, showing the apparatus in the position it assumes 60 immediately before dumping; and Fig. 4, a similar view, showing the apparatus of Fig. 3 in the act of dumping.

Referring to the construction illustrated in Figs. 1 and 2, the inclined cableway commonly used in apparatus of this general type and forming a guide-way is represented at 5, this cable in practice being anchored at its lower end in any suitable manner, and at its upper end supported at a 70 higher elevation and in a manner adapting it to be slackened and made taut at will, all as is well understood in the art and therefore does not require illustration. Slidably mounted on the cableway 5 is a carriage 6, 75 which may be of any suitable construction, that shown comprising a pair of side frames 7, one only of which is shown, which are spaced apart at opposite sides of the cableway 5 and are connected together, as for example, by the cross-pins 8, 9, 10, 11, 12, 13 and 14, with suitable spacers between these frames to hold them apart, as is common in constructions of this general character. The pins 8 and 9 form supports for 80 sheaves 15 and 16, respectively, which rest upon the cableway 5. A dumping-scraper or bucket, represented at 17, and which is supported from the carriage 6, is provided at its forward open end with a cutting edge 90 portion 18, adjacent to which is a bail 19, and at its rear, open end portion is equipped with a gate-valve 20 formed of a curved end-plate 21, which extends across the rear, open end of the bucket, and side-plates 22 at 95 opposite sides of the bucket, at which the gate-valve is pivotally supported on the bucket as through the medium of pivots at opposite sides thereof, one of these pivots being represented at 23.

The main section of the hauling-line is represented at 24, this line, in practice, usually being wound upon a drum or windlass for controlling the movements of the carriage upon the cableway. The section 24 105 is connected with a block 25, equipped with a

- sheave 26, this block being also connected with chains or cables 27 which, in turn, are connected with the forward portion of the bucket 17 at opposite sides thereof, as represented at 28. The bucket 17 is hung from the carriage 7 by the chains or cables 29, which connect with the rear end of the bucket, and by a chain or cable 30, which is connected with the bail 19 of the bucket, 5 the elements 29 and 30 being of such length that the bucket will incline downwardly at its lower end in load-carrying position. The cable 31 connects at its lower end with the lower end of the valve 20, thence passes upwardly around a sheave 32 on the cross-pin 10, thence over a sheave 33 on the pin 14, and thence under the sheave 26 to a traveling-block 34, to which it is connected, this block carrying a sheave 35, on which the 10 block rollingly bears against and is supported on, the cable 5, this block co-operating with a stop 36 on this cable for a purpose hereinafter described. The cable 31, intermediate the sheaves 26 and 33, is connected 15 as indicated at 37 with one end of a cable 38, which passes over a sheave 39 journaled on the pin 13, the lower end of this cable connecting with the bail 19.

- In the operation of the apparatus, the operator slackens the cable 5 and by drawing on the hauling-line 24 pulls the scraper-bucket through the material to be transferred, the material filling the bucket. The cableway 5 is then drawn sufficiently taut to 20 lift the bucket out of engagement with the material and the carriage and bucket are drawn up the cableway by pulling on the hauling-line 24, the bucket assuming the load-carrying position illustrated in Fig. 1. 25 In the movement of the carriage and bucket up the cableway 5 movement of the block 34 is arrested by the block engaging the stop 36 and continued pulling on the hauling-line 24 therefore operates to cause the cables 31 30 and 38 to travel at twice the speed of the cables 24 and 27, with the result of swinging the gate 20 upwardly to uncover the open, rear, end of the bucket and tilt the bucket on the cable 29 in counter-clockwise 35 direction in Fig. 1, thus causing the contents of the bucket to discharge therefrom through the uncovered open, rear, end of the bucket. When the line 24 is slackened the bucket assumes the position shown in Fig. 41, and the bucket and carriage run down the cable-way 5, the latter, after the bucket reaches the point of loading, being again slackened and the filling, carrying and dumping operations repeated.
- 60 The construction illustrated in Figs. 3 and 4 is the same as that shown in the preceding figures except that instead of supporting the bucket 17 from the separate cables 29 and 30 it is supported from a single cable 65 40, which is secured at its opposite ends sub-

stantially at the same points as the cables 29 and 30 are connected with the bucket, and extends slidably over a sheave 41 rotatably mounted on the carriage 6. In this construction the cable 38 carries a stop 42 70 adapted to engage the carriage 6 and prevent the bucket, when the parts of the structure are in the normal load-carrying position represented in Fig. 1, from tilting downwardly at its forward end to discharge position. 75

In the dumping operation effected by continued pull on the hauling-line 24 after the block 34 engages the stop 36, the forward movement of the cables 31 and 38 relative to the hauling-line 24, operates to raise the 80 valve 21 and swing the bucket in counter-clockwise direction as shown in the drawings to dumping position, the cable 40 running over the pulley 41 in this operation.

It will be readily understood from the 85 foregoing that while pressure of the material in the bucket against the valve 20 is reduced to the minimum, the feature of tilting the bucket as explained insures the discharge of the material from the bucket regardless of 90 its character, and thereby the apparatus is caused to tilt with comparative ease positively. Furthermore in the particular constructions shown the bucket is maintained in load-carrying position even should the 95 hauling-line become slackened as sometimes occurs in the hauling of the bucket to dumping position and thus accidental dumping is prevented.

While I have illustrated and described 100 two forms of construction in which my invention may be embodied, I do not wish to be understood as intending to limit it thereto, as the same may be variously modified and altered and the invention provided in 105 other forms, without departing from the spirit of my invention, it being my intention to claim my invention as fully and completely as the prior state of the art will permit.

110 What I regard as new and desire to secure by Letters Patent is:

1. The combination of a guideway, a rear-dumping scraper-bucket, having a valve controlling its open rear end, means supporting said bucket on said guideway, means for shifting said bucket along said guideway from loading to dumping position, said first-named means operating to normally hold said bucket in load-carrying position regardless of the slackening of said second-named means, and means for producing relative movement of said bucket and valve and tilting said bucket rearwardly to cause said parts to occupy dumping position. 115 120 125

2. The combination of a guideway, a rear-dumping scraper-bucket, having a valve controlling its open rear end, means supporting said bucket on said guideway, means for shifting said bucket along said guideway 130

from loading to dumping position, said first-named means operating to normally hold said bucket in load-carrying position regardless of the slackening of said second-named means, and means for lifting said valve and tilting said bucket rearwardly to cause said parts to occupy dumping position.

3. The combination of a guideway, a carriage movable along said guideway, a rear-dumping scraper-bucket having a valve controlling its open rear end, means supporting said bucket from said carriage, means for shifting said bucket and carriage from loading to dumping position, said first-named means operating to normally hold said bucket in load-carrying position regardless of the slackening of said first-named means, and means for producing relative movement of said bucket and valve and tilting said bucket rearwardly to cause said parts to occupy dumping position.

4. The combination of a guideway, a carriage movable along said guideway, a rear-dumping scraper-bucket having a valve controlling its open rear end, means supporting said bucket from said carriage, means for shifting said bucket and carriage from loading to dumping position, said first-named means operating to normally hold said bucket in load-carrying position regardless of the slackening of said second-named means, and means for lifting said valve and tilting said bucket rearwardly to cause said parts to occupy dumping position.

35 5. The combination of a support, a carriage movable thereon, a rear-dumping scraper-bucket having a valve controlling its open rear end, a hauling-line connected with said bucket, means for supporting said bucket in load-carrying position on said carriage independently of said hauling-line, and means extending into engagement with said carriage for effecting relative movement of said valve and bucket and tilting said bucket rearwardly to cause said parts to occupy dumping position.

6. The combination of a support, a carriage movable thereon, a rear-dumping scraper-bucket having a valve controlling its open rear end, a hauling-line connected with said bucket, means for supporting said bucket in load-carrying position on said carriage independently of said hauling-line, and means extending into engagement with said carriage for lifting said valve and tilting said bucket rearwardly to cause said parts to occupy dumping position.

7. The combination of a support, a rear-dumping scraper-bucket having a valve controlling its open rear end, means supporting said bucket from said support, means for shifting said bucket from loading to dumping position, and means operating by continuous forward pull on said second-named means to produce relative movement of said

bucket and valve and tilt said bucket rearwardly to cause said parts to occupy dumping position.

8. The combination of a support, a rear-dumping scraper-bucket having a valve controlling its open rear end, means supporting said bucket from said support, means for shifting said bucket from loading to dumping position, and means operating by continuous forward pull on said second-named means to lift said valve and tilt said bucket rearwardly to cause said parts to occupy dumping position.

9. The combination of a guideway, a carriage movable along said guideway, a rear-dumping scraper-bucket having a valve controlling its open rear end, means supporting said bucket from said carriage, means for shifting said bucket and carriage along said guideway from loading to dumping position, and means operating by continuous forward pull on said second-named means to produce relative movement of said bucket and valve and tilt said bucket rearwardly to cause said parts to occupy dumping position.

10. The combination of a guideway, a carriage movable along said guideway, a rear-dumping scraper-bucket having a valve controlling its open rear end, means supporting said bucket from said carriage, means for shifting said bucket and carriage along said guideway from loading to dumping position, and means operating by continuous forward pull on said second-named means to lift said valve and tilt said bucket rearwardly to cause said parts to occupy dumping position.

11. The combination of a support, a carriage movable thereon, a rear-dumping scraper-bucket having a valve controlling its open rear end, a hauling-line connected with said bucket, means for supporting said bucket in load-carrying position on said support independently of said hauling-line, and means extending into engagement with said carriage and operated by continuous forward pull on said hauling-line, for effecting relative movement of said valve and bucket and tilting said bucket rearwardly to cause said parts to occupy dumping position.

12. The combination of a support, a carriage movable thereon, a rear-dumping scraper-bucket having a valve controlling its open rear end, a hauling-line connected with said bucket, means for supporting said bucket in load-carrying position on said support independently of said hauling-line, and means extending into engagement with said carriage and operated by continuous forward pull on said hauling line, for lifting said valve and tilting said bucket rearwardly to cause said parts to occupy dumping position.

13. The combination of a support, a carriage movable thereon, a rear-dumping

scraper-bucket having a valve controlling its open rear end, a hauling-line connected with said bucket, means supporting said bucket from said carriage, a block movable along 5 said guideway, a stop located in the path of movement of said block at the point of dumping, and means connected with said block and with said valve and the forward

portion of said bucket and operatively engaging said hauling-line in a manner to permit relative movement of these parts and operating when said block engages said stop to lift said valve and tilt the bucket rearwardly. 10

LOUIS E. DIERKS.
